UNITED STATES PATENT OFFICE.

EDWIN HAVILAND, OF PLAINFIELD, NEW JERSEY.

DESIGN FOR AN EARTHENWARE DISH.

SPECIFICATION forming part of Design No. 14,948, dated April 8, 1884.

Application filed December 1, 1883. Term of patent 34 years.

To all whom it may concern:

Be it known that I, EDWIN HAVILAND, a citizen of the United States, residing at Plainfield, in the county of Union and State of New Jersey, have invented or produced a new and original Design for Earthenware Dishes, of which the following is a specification.

My design relates, in general, to earthenware dishes, and particularly to the several pieces constituting table or toilet sets of china or other earthenware. I have selected the soup-tureen from among the several pieces constituting a dinner set, as that embodies all the novel features of my design.

Figure 1 of the accompanying drawings is a side elevation of the soup-tureen. Fig. 2 is a plan thereof, and Fig. 3 is an end elevation thereof.

The dish A is formed with sides which are substantially rectangular when viewed in plan, but are curved very slightly inward, the opposite sides being somewhat nearer to each other at their middles than they are near their extremities, as denoted by the line *a a* in Fig.

25. The corners are rounded with the curve shown in that figure. The dish, when viewed in side or end elevation, is seen to curve downwardly and inwardly from its widest point at *a* until the foot *b* is reached, and to curve upwardly and inwardly from *a* until the neck *c* is reached. This line is shown clearly in Figs. 1 and 3. The cover B is of similar outline to the dish when viewed in plan, its side lines being slightly concaved and its corners rounded, as shown in Fig. 2. Viewed in side or end elevation, it is seen to be rounded on top by a gentle curve, a flat top being avoided. This contour is shown by the line *d d* in Figs. 1 and 3. Just above and within the

40. neck the line of the cover descends somewhat abruptly at *e* and joins the wide flange *f*, which projects almost horizontally and extends considerably beyond the neck *c*. This descent *e* is sharp and abrupt, but is not deep. This 45. short descent, in connection with the wide flange and curved top of the cover and the general outline of the latter, when viewed in plan, constitutes one feature of my design.

The handles C C are rectangular, that on the 50. cover having a straight bar joined to two straight uprights, and those on the dish having a straight bar joined to two arms which

are curved outwardly. The opposite surfaces of the handles are formed with beaded or rope-like corrugations. At the base of each handle is a design in relief, consisting of a leaf, *g*, and two budded stems or tendrils, *h h*. The latter are in delicate lines and low relief, and may be varied somewhat—as, for instance, to represent a spray of small delicate leaves—55 without changing the general effect of the ornamentation. On the cover there are two leaves, *g g*, one beyond each upright of the handle, and the stems or sprays *h h* extend from the leaves toward each other. The corrugations on the handle extend down upon the cover and terminate in curves, as shown in Fig. 2. On the dish there is but one leaf *g* to each handle, and both ends of the line of corrugations on the outer side of the handle 60 extend down upon the dish for a considerable distance, and terminate in curves, as clearly shown at *i i* in Fig. 3. From the root of the handle spring two raised ribs, *j*, simulating slender branches, which extend to the leaf *g* 65 and appear to pass under the same, reappearing as the stems *h h*, which extend thence upwardly and toward both sides, passing apparently beneath the beaded curves *i i*. 70

My design is applicable to covered or uncovered dishes, and some one or more of the segregable parts thereof are applicable to all or most of the pieces constituting table or toilet sets.

I claim—

1. In a design for earthenware dishes, the configuration of the cover as shown, the same having, as seen in plan, a general rectangular outline with rounded corners and slightly-concaved sides, and, as seen in elevation, a convex 85 top surface, a short abrupt rounded descent, *c*, and a wide flat projecting flange, *f*.

2. In a design for earthenware dishes, the handle C, formed of a straight bar joined rectangularly to two arms, and with a row of rope-like or beaded corrugations traversing said bar and arms, as shown and described.

3. In a design for earthenware dishes, the handle C, formed with two rows of rope-like or beaded corrugations traversing its opposite sides, and extending to and upon the surface of the dish or cover and there terminating in curves, as shown and described.

4. In a design for earthenware dishes, the

ornamentation in relief on the dish at the base of the handle, the same consisting of a single leaf, *g*, arranged beneath the middle of the handle, in connection with stems *j j*, joining it, and with sprays *h h*, extending laterally from it, as shown in Fig. 3.

5. In a design for earthenware dishes, the handle traversed by a row of corrugations, which extend beyond the base of the handle

and terminate upon the surface of the dish, as shown, with leaf *g* and sprays *h h*.

In witness whereof I have hereunto signed my name in the presence of two subscribing witnesses.

EDWIN HAVILAND.
